UNITED STATES PATENT OFFICE.

STEPHEN F. McDONALD, OF CLEVELAND, OHIO.

VENTILATOR.

1,336,470.

Specification of Letters Patent. Patented Apr. 13, 1920.

Application filed September 5, 1916. Serial No. 118,386.

To all whom it may concern:

Be it known that I, STEPHEN F. McDONALD, a citizen of the United States, residing at Cleveland, in the county of Cuyahoga and State of Ohio, have invented a certain new and useful Improvement in Ventilators, of which the following is a full, clear, and exact description, reference being had to the accompanying drawings.

10 This invention relates to ventilators, and more particularly to ventilators which are intended or adapted for use with cars or like movable objects. It is the general purpose of this invention to provide a ventilator 15 which will be extremely efficient in inducing a circulation of air through such objects in order to secure proper ventilation and one which is peculiarly well adapted and equipped for all ordinary incidents of use 20 in its particular environment. Further objects of the invention will appear in the detailed description hereinafter and will be realized in and through the combinations of 25 elements embodied in the claims hereto annexed and illustrated in the drawings forming part hereof, wherein Figure 1 represents a side elevation of a railway car having my invention applied thereto; Fig. 2 a longitudinal sectional view through a ventilator constructed in accordance with my 30 invention; Fig. 3 a view, in transverse section and partly in elevation, of the said ventilator and the parts with which it is associated; Fig. 4 a perspective view of such 35 ventilator; and Fig. 5 an end elevation of the ventilator as applied to the top of a car, the ventilator being connected to an elbow whereby the body is turned at 90 degrees with respect to the position occupied 40 in Figs. 1, 3 and 4.

Describing by reference characters the various parts illustrated herein, 1 denotes a railway car having the usual roof, said roof comprising the lower section 2, the 45 upper section 3, and the side walls 4. The side walls 4, as is well known, are usually provided with transoms for purposes of ventilation. I have shown several of my ventilators as employed in place of these transoms. In Figs. 1, 2 and 3 the ventilators are connected by horizontal air shafts 5 with the space between the roof sections 2 and 3, said shafts being mounted in the side

walls 4. For convenience of description, the ventilator shown in Figs. 2, 3 and 4 will 55 be assumed to have been turned on its side and the wall opposite the air shaft 5 will be considered as the "top", in which position one of the sides becomes the top, the other side the bottom, and the roof opposite the 60 air shaft 5 becomes the outer side. The head is divided by a partition 6 into two sections each of which acts as a front and a rear section, according to the direction in which the car is moving, the two sections being symmetrical, it being understood (as well as apparent from the drawings), that the ventilator is intended to be used either in the side position shown in Figs. 1 to 4 inclusive 65 or in the upright position indicated in Fig. 70 5, the flow of air which exercises its aspirating effect upon the air shaft being produced by the movement of the car and the consequent movement of the ventilator or ventilators attached thereto. The ventilator body 75 comprises a top or cover wall 7 and a correspondingly shaped inner or bottom wall 8, the wall 8 having the necessary opening for the air shaft 5. These walls are given the peculiar formation shown more particularly 80 in Figs. 2 and 4. Each wall has on each side thereof a central concave edge 9. From each end of this concave portion each edge is tapered or inclined, as shown at 10, a short distance, such inclined edge portion 85 merging with the more sharply inclined edge portion 11, the edge portions 11 meeting at a point, indicated at 12. The inclined edges 11 are connected by correspondingly inclined end walls 13 forming front 90 and rear wedges, and the concaved edges 9 are connected by correspondingly concaved side walls 14.

15 and 16 denote walls connecting the walls 7 and 8 and extending inwardly from the ends 14^a of the concave walls 14, said walls 15 extending as close as conveniently possible to the opening provided in the bottom plate 8 for the air shaft 5. Each wall 15 is provided with a short flange or projection 15^a forming a baffle extending toward the central portion of the ventilator body and each wall 16 is provided with a similar but longer flange or projection 16^a forming a similar but longer baffle. 100 105

It will be observed that tapered outwardly

convergent ducts 17 are provided between each wall 15, 16, and the adjacent inclined side wall 13. The space between the adjacent ends of the walls 15 and 16 is covered by a screen 18 which may be of wire gauze and which is preferably convex, there being a convex wall 19 located between said screen and the adjacent end of the ventilator head and forming a distributing passageway 17^a 10 communicating with the ducts 17.

As the ventilator head thus far described may be used either in the upright position shown in Fig. 5, or on its side, as indicated in the other figures, it is adapted for use 15 for either position. When used in the upright position, the air shaft 5^a will be connected to the bottom wall of the ventilator by means of an elbow 22. The ventilator is preferably provided with a sloping roof, indicated generally at 20 and preferably comprising six generally triangular surfaces 20^a-20^f inclusive each surface extending from a common apex 21 to an edge of the top wall 7.

25 The action of the ventilator is the same and is distinctive, whether it be placed on its side or in the vertical position indicated in Fig. 5. This action is illustrated in Fig. 2, where the ventilator is shown as on its side, the direction of movement of the air current being indicated by the arrow 23 and the action of the air current upon the ventilator head and the air shaft being indicated by the other arrows on said figure. The air 30 current is split by the wedge formed by the end of the ventilator head presented there- toward and flows along the sides of such wedge. Passing across the mouths 17^b of the ducts 17, it exercises an aspirating effect 35 upon said ducts causing a movement of air through the air shaft and the ventilator body on that side of the partition 6. This aspirating effect is enhanced by reason of the fact that the outer ends of the walls 15 and 40 16 project beyond the outer ends of the inclined walls 13. The air follows the direction of the arrows across the concave walls 14, and by such walls, is given a reverse eddy 45 at the mouths of the ducts 17 at the opposite side of the ventilator head, as indicated by the arrows, it being finally discharged beyond the rear end of the ventilator. This 50 reverse movement of the air causes an aspirating effect upon the ducts 17 at the rear 55 side of the partition 6, whereby all of the ducts 17 coöperate in the removal of air from the air shaft and through the ventilator body.

Reference has been made to the baffles 16^a. 60 These are somewhat longer than the baffles 15^a; the baffles are necessary only when the ventilator is placed on its side, serving to prevent any rain which may enter the upper ducts 17, 17^a from getting into the ventilator

body, the lower baffles, by projecting inwardly further than the upper baffles, serve to direct through the ducts 17 therebeneath any moisture that may collect or strike thereupon. When the ventilator is used in the vertical position shown in Fig. 5, 70 these baffles will probably be unnecessary. Through the use of the screens 18 and the baffles 15^a and 16^a, no cinders, dust, or water will enter the car.

The construction shown and described 75 herein has proven efficient in providing for all ordinary incidents of use and has proven particularly efficient in connection with the ventilation of vehicles.

Having thus described my invention, what 80 I claim is:

1. A double-ended symmetrical exhaust ventilator comprising an air shaft, a head comprising a base having a centrally located opening communicating with said air shaft, a top or roof above said base, a pair of forwardly converging side walls and a pair of rearwardly converging side walls interposed between said base and said top or roof, 85 said pairs of side walls providing between 90 their convergent ends a forwardly and a rearwardly directed outlet, respectively, communicating with the air shaft, other side walls extending between the base and top and connecting the divergent ends of the 95 first mentioned walls, and a pair of forwardly and a pair of rearwardly inclined end walls, the walls of each pair meeting to form respectively a forwardly and a rearwardly directed wedge, the rear ends of 100 one pair of the end walls and the front ends of the other pair of the last mentioned walls overlapping the corresponding portions of the first mentioned walls and forming with such portions rearwardly and forwardly 105 convergent ducts, respectively, each having a discharge outlet across which the air flowing on each side of each wedge is delivered, thereby to exercise an aspirating effect upon 110 said ducts, the first mentioned outlets, and the air shaft.

2. A double-ended symmetrical exhaust ventilator comprising an air shaft, a head comprising a base having a centrally located opening communicating with said air shaft, 115 a top or roof above said base, a pair of forwardly converging side walls and a pair of rearwardly converging side walls interposed between said base and said top or roof, said pairs of side walls providing between their 120 convergent ends a forwardly and a rearwardly directed outlet, respectively, communicating with the air shaft, concave side walls extending between the base and top and connecting the divergent ends of the 125 first mentioned walls, and a pair of forwardly and a pair of rearwardly inclined end walls, the walls of each pair meeting

to form respectively a forwardly and a rearwardly directed wedge, the rear ends of one pair of the last mentioned walls and the front ends of the other pair of the last mentioned walls overlapping the corresponding portions of the first mentioned walls and forming with such portions rearwardly and forwardly convergent ducts, respectively, each having a discharge outlet across which the air flowing on each side of each wedge is delivered, thereby to exercise an aspirating effect upon said ducts, the first mentioned outlets, and the air shaft.

3. A double-ended symmetrical exhaust ventilator comprising an air shaft, a head comprising a base having a centrally located opening communicating with said air shaft, a top or roof above said base, a pair of forwardly converging side walls and a pair of rearwardly converging side walls interposed between said base and said top or roof, said pairs of side walls providing between their convergent ends a forwardly and a rearwardly directed outlet, respectively, communicating with the air shaft, concave side walls extending between the base and top and connecting the divergent ends of the first mentioned walls, a pair of forwardly and a pair of rearwardly inclined end walls, the walls of each pair meeting to form respectively a forwardly and a rearwardly directed wedge, the rear ends of one pair of the last mentioned walls and the front ends of the other pair of the last mentioned walls overlapping the corresponding portions of the first mentioned walls and forming with such portions rearwardly and forwardly convergent ducts, respectively, each having a discharge outlet across which the air flowing on each side of each wedge is delivered, thereby to exercise an aspirating effect upon the said ducts and outlets and upon the air shaft, and a vertical partition extending between the top or roof and the base and connecting the central portions of the concave side walls and dividing the head into front and rear sections each communicating with the air shaft.

4. A double-ended symmetrical exhaust ventilator comprising an air shaft, a head comprising a base having a centrally located opening communicating with said air shaft, a top or roof above said base, a pair of forwardly converging side walls and a pair of rearwardly converging side walls interposed between said base and said top or roof, said pairs of side walls providing between their convergent ends a forwardly and a rearwardly directed outlet, respectively, communicating with the air shaft, other side walls extending between the base and top and connecting the divergent ends of the first mentioned walls, a pair of forwardly and a pair of rearwardly inclined end walls,

the walls of each pair of end walls meeting to form respectively a forwardly and a rearwardly directed wedge, the rear ends of one pair of the last mentioned walls and the front ends of the other pair of the last mentioned walls overlapping the corresponding portions of the first mentioned walls and forming with such portions rearwardly and forwardly convergent ducts, respectively, each having a discharge outlet across which the air flowing on each side of each wedge is delivered, thereby to exercise an aspirating effect upon the ducts, the first mentioned outlets, and the air shaft, and a forwardly and a rearwardly convex baffle located respectively in front and at the rear of the first mentioned outlets and respectively connecting the forwardly and the rearwardly inclined end walls.

5. A double-ended symmetrical exhaust ventilator comprising an air shaft, a head comprising a base having a centrally located opening communicating with said air shaft, a top or roof above said base, a pair of forwardly converging side walls and a pair of rearwardly converging side walls interposed between said base and said top or roof, said pairs of side walls providing between their convergent ends a forwardly and a rearwardly directed outlet, respectively, communicating with the air shaft, a baffle projecting rearwardly and inwardly from the front end of each of the forwardly converging walls, a baffle projecting forwardly and inwardly from the rear end of each of the rearwardly converging walls, other side walls extending between the base and top and connecting the divergent ends of the first mentioned walls, and a pair of forwardly and a pair of rearwardly inclined end walls, the walls of each pair of end walls meeting to form respectively a forwardly and a rearwardly directed wedge, the rear ends of one pair of the last mentioned walls and the front ends of the other pair of the last mentioned walls overlapping the corresponding portions of the first mentioned walls and forming with such portions rearwardly and forwardly convergent ducts, respectively, each having a discharge outlet across which the air flowing on each side of each wedge is delivered, thereby to exercise an aspirating effect upon the ducts, the first mentioned outlets, and the air shaft.

6. An exhaust ventilator comprising an air shaft, a head comprising a base having an opening communicating with said air shaft, a top or roof above said base, a pair of forwardly converging side walls interposed between said base and said top or roof and providing between their convergent ends a forwardly directed outlet communicating with the air shaft, and a pair of forwardly inclined end walls meeting in front of the

said outlet to form a wedge, the rear end of each of the last mentioned walls overlapping the rear portion of one of the first mentioned walls and forming with such overlapped portions rearwardly convergent ducts each having a narrow discharge outlet across which the air flowing on each side of such

wedge is delivered, thereby to exercise an aspirating effect upon the ducts, the first mentioned outlet, and the air shaft.

10

In testimony whereof I hereunto affix my signature.

STEPHEN F. McDONALD.
